ROCK DRILL WITH BLOWING DEVICE

Earl B. Lear, Detroit, Mich., assignor to Chicago
Pneumatic Tool Company, New York, N. Y., a
corporation of New Jersey

Application June 3, 1936, Serial No. 83,210

1 Claim. (Cl. 121—10)

The present invention relates to fluid pressure operated percussive tools, such as rock drills, and is concerned particularly with the throttle and distributing valves for such tools.

Among the objects of the invention are to reduce the manufacturing cost and weight of a rock drill and to insure positive hole cleaning. Accordingly, a throttle valve and a blower valve are combined into a unitary structure so arranged that each time the throttle valve is turned on or off a stream of air is directed through the bore in the drill steel to remove the detritus from the hole. The throttle valve is so constructed that it closes the central exhaust port for the cylinder whenever the throttle valve is in either the blowing or closed position to prevent the admission of dirt through the exhaust port to the cylinder bore.

A feature of the invention resides in fluid pressure means for holding the distributing valve immovable against one of its seats to admit compressed air to the rear end of the cylinder bore from whence the air is conducted through the hollow piston to the drill steel bore with a minimum of leakage. The means for holding the distributing valve in position comprises ports in a manipulative throttle valve, one of which admits live air to one face of the distributing valve and another of which exhausts the opposing face of the distributing valve.

Another object of the invention is the provision of a distributing valve of the disc type having means for centering the valve relative to its seats and for prolonging the life of the valve. The distributing valve is in the form of a disc perforated to receive a bushing and having a hub adapted to fit the bushing and guide the valve in its movement.

Other objects and features of the invention will appear more clearly from the accompanying drawings and appended claim.

In the drawings which illustrate one embodiment of the invention:

Fig. 1 is an elevation of a portion of a rock drill of the sinker type, the throttle valve handle being shown in drilling position;

Fig. 2 is a section through the plane indicated by the arrows 2—2 in Figs. 1 and 6;

Fig. 3 is a view similar to Fig. 2 but partly in elevation and partly schematic and showing the combined throttle and blower valve in blowing position;

Fig. 4 is a fragmentary schematic view showing two different sections of the throttle valve

and associated ports, the valve being arranged in the off-position;

Fig. 5 is a view similar to Fig. 4 but with the throttle valve adjusted to the drilling position;

Fig. 6 is an end elevation looking from left toward right in Fig. 1;

Fig. 7 is a cross-section as indicated by the arrows 1—1 in Fig. 1, but with the throttle valve in blowing position;

Fig. 8 is a fragmentary longitudinal section showing the cylinder, piston and distributing valve, certain passages being, for convenience, shown in simplified form;

Fig. 9 is a fragmentary longitudinal sectional view on an enlarged scale showing the distributing valve and valve chest, and

Fig. 10 is a sectional view of the distributing valve on the same scale as Fig. 9.

The rock drill illustrated in the drawings comprises a cylinder 11 having a piston 12 reciprocably mounted therein. The forward part of the piston has a grooved extension 13 which passes through a front cylinder washer 14 and into fluted engagement with an internally grooved chuck nut 15 which is keyed to a chuck 16. The washer 14 forms a closure for the front end of the cylinder. At the end of its forward stroke the piston strikes the drill steel 17 having a non-circular fit with the chuck. The chuck nut 15, chuck 16, and washer 14 are held in position by means of a front head 19 which may be fastened to the cylinder by any suitable means, such as elongated bolts 18 shown in Figs. 1, 6 and 7.

The rear of the cylinder 11 is closed by a back cylinder washer 20 which cooperates with a valve case 21 to form a housing for a distributing valve 22. A ratchet ring 23 is positioned between the valve case and a backhead 24, the backhead being adapted to seat the heads 18a of the bolts 18. The backhead is provided with arms 25 for supporting a grip handle 26. A plate 27 at the rear end of the ratchet ring cooperates with the backhead 24 to provide a lubricant reservoir 28.

Any suitable means may be provided for rotating the piston 12 step-by-step as it reciprocates. As shown, the rotating mechanism comprises a rifle nut 30 screwed to the piston, a rifle bar 31 spirally splined to the nut, and pawls 32 carried by the head of the rifle bar and engageable with the internally toothed ratchet ring 23. A bushing 33, surrounding the rifle bar, provides a support for valve 22.

The distributing valve 22 is shown most clearly in Figs. 9 and 10. It comprises a disk portion 35

55 surrounding the rifle bar, provides a support for valve 22.

and a hub 36 integral therewith. The forward face of the disc portion is a plane surface adapted to rest on one or the other of the seats 37f and 37r formed on the member 20. Valve seats 5 37f and 37r are flat and angularly disposed relative to each other so that the planes of the seats diverge forwardly. The seats have recesses 38f and 38r. A port 40 connects the recess 38r with the rear end of the cylinder and a passage 41 10 connects recess 38f with the front end of the cylinder thereby to admit live pressure fluid alternately to opposite sides of the piston head 12.

The interior of the hub 36 is defined by frusto-conical surfaces 36a and 36b, the included angle 15 between such surfaces being equal to the included angle between the seats 37f and 37r so that the interior of the hub embraces the bushing 33 on opposite sides when the disc portion 35 rests on either seat. The upper edge 36c of the hub is bevelled to fit the adjacent portion of the valve 20 chest 21. The hub 36 guides the valve in its movement, permits rapid tripping of the valve and prolongs the life of the same. The hub also centers the valve with respect to its seats and associated passages and thereby insures an adequate supply of pressure fluid with minimum leakage. The valve 22 is free to be oriented about its axis to distribute wear.

When the machine is conditioned for drilling, 30 the operation is as follows: Live air is admitted (by throttle means hereinafter described) to a chamber 43 in the valve housing 20, 21, the rear face of the distributing valve 22 being exposed to pressure fluid in said chamber. Assuming the distributing valve and piston occupy the position shown in Figs. 8 and 9, live air passes around the peripheral edge of the valve disc portion 35 over the seat 37r and through recess 38r and port 40 to the rear end of the cylinder, thereby forcing the piston 12 forwardly. The air in front of the piston head 12 is vented through exhaust port 44 until the piston head has covered the exhaust port. The piston continues moving forward under its momentum and delivers a blow to the drill 45 steel 17. Toward the end of the forward stroke of the piston the valve is tripped to the position shown in Fig. 2 by the combined action of a reduction in pressure in the recess 38r caused by the uncovering of the exhaust port 44, and the building up of pressure at the front end of the 50 cylinder due to the compression of air trapped in front of the piston head 12 which is transmitted to the recess 38f by means of passage 41. After the valve has been tripped, live pressure 55 fluid from chamber 43 passes around the peripheral edge of the distributing valve over seat 37f and through recess 38f and passage 41 to the front end of the cylinder 11 to force the piston rearwardly. The air at the rear end of the cylinder is first exhausted through port 44 and then compressed after the piston head covers the exhaust port. When the front edge of the piston head uncovers the exhaust port, the drop in pressure at the front end of the cylinder causes a corresponding reduction in pressure 60 in the recess 38f which, together with the increase of pressure in recess 38r, is effective to trip the valve to the position shown in Fig. 9, thus completing a cycle of operation.

70 It is desirable to provide means for blowing a stream of live air through the drill steel 17 to clear the bore hole of accumulated detritus. Accordingly, the invention comprises a blowing arrangement which is operable whenever the throttle valve is turned on or off and which does not

require the manipulation of any device other than the throttle valve.

The throttle valve 45, as shown in Fig. 7, is generally of frusto-conical shape to fit a correspondingly shaped bore in a projection 46 on the outside of the cylinder 11. A handle 47, having an extension on the valve, is keyed thereto at 48 and is retained by a nut 49 threaded on the extremity of the throttle valve. A spring-pressed detent 50 carried by the handle is adapted to register with any one of three depressions 51 on the cylinder projection 46 for yieldingly locking the handle and valve in selected position of adjustment. A sleeve 53 threaded to the cylinder projection 46, provides a retainer for an air supply hose 54 10 which communicates with recess 55 in the throttle valve.

As shown in Figs. 3, 4 and 5, the live air recess 55 communicates with two ports in the throttle valve 45 adapted selectively to admit pressure 20 fluid to passage 57 leading to the supply chamber 43 in the distributing valve housing 20, 21. One of these ports 58 registers with passage 57 in the drilling position and the other port 59 registers in the blowing position. The throttle valve 45 has a groove 60 out of communication with the live air recess 55 and positioned to connect the main exhaust port 44 with the exhaust port 61 in the projection 46 when the throttle valve is adjusted to 25 drilling position. A supplementary groove 60a establishes communication between exhaust port 61 and a passage 63 leading to recess 38f in the distributing valve housing 21 to vent the recess when the throttle valve is adjusted to blowing 30 position.

When the throttle handle 47 is in the drilling position, shown in Figs. 1 and 2, live air is supplied to the distributing valve case 21 through port 58 in the throttle valve and passage 57 in 40 the cylinder. At the same time the central exhaust port 44 in the cylinder is vented through groove 60 in the throttle valve. In order to stop the operation of the machine, the throttle handle 47 must first be turned to the blowing position shown in Figs. 3 and 7. In this position, the throttle valve supplies live air to the distributing valve chamber 43 by means of port 59 and passage 57. Simultaneously the central exhaust port 44 in the cylinder is closed by the throttle valve, 45 and the recess 38f, facing one side of the distributing valve, is vented through cylinder passage 63 and throttle valve grooves 60a and 60. The preponderance of pressure on the rear face of that portion of the distributing valve which 50 overlies recess 38f moves the valve to the position shown in Fig. 9 and holds the valve against seat 37f to admit live pressure fluid through port 40 to the rear end of the cylinder. The pressure fluid admitted through port 40 drives the piston 60 forwardly until it is stopped by engagement with the drill steel. Pressure fluid in back of the piston passes through the clearance between the splines on the rifle bar 31 and rifle nut 30 and through the interior of the hollow piston and drill steel to 65 blow the detritus from the bore hole. When the valve handle 47 is adjusted to the off position, the live air recess 55 in the throttle valve is cut off from communication with the cylinder passages, and the main exhaust port 44 in the cylinder is 70 closed to prevent the admission of dust to the interior of the cylinder.

What is claimed is:

A fluid actuated rock drill comprising a cylinder, a hollow piston reciprocating therein, a hol- 75

low drill steel adapted to receive blows from the piston, a distributing valve chest, passages leading from said chest to the respective ends of the cylinder, a main exhaust port for the cylinder, a supplementary exhaust port for the front end of the cylinder, a fluid pressure supply chamber in the valve chest, a distributing valve in the chest controlling communication between said supply chamber and said passages, a source of live pressure fluid, connections between said source and said supply chamber, a housing for a throttle

valve, a manipulative throttle valve mounted therein, characterized in that said throttle valve and housing are provided with selectively operable means for venting either exhaust port and simultaneously closing the other exhaust port, and vice versa, and are provided with selectively operable means for opening and closing the connections between the source of live pressure fluid and the supply chamber in the distributing valve chest. 5
